UNITED STATES PATENT OFFICE.

EDWARD C. RICHARD AND HARGRAVES GILL, OF WESTBORO, MASSACHUSETTS, ASSIGNORS TO WESTBORO WEAVING CO., OF NEW YORK, N. Y., A CORPORATION OF NEW YORK.

SHUTTLE.

Application filed November 3, 1923. Serial No. 672,472.

This invention relates to improvements in shuttles, and, particularly, to shuttles used for weaving tape and other narrow fabrics.

One of the objects of our invention is to provide a shuttle having a tension device that will maintain a uniform tension on the thread after it leaves the bobbin, and which will reduce to a minimum the possibility of breaking the same.

10 Another object of our invention is to provide a shuttle that will contain a larger amount of thread without increasing the size of the shuttle.

15 A further object of our invention is to provide a shuttle that will accomplish the foregoing objects with simplified means.

With such objects in view, our invention consists in the construction and combination of parts as hereinafter described and 20 claimed.

In the accompanying drawings,

Fig. 1 is a top or plan view, with portions broken away;

25 Fig. 2 is a section on the line 2—2 of Fig. 1;

Fig. 3 is a fragmentary view on the line 3—3 of Fig. 1;

Fig. 4 is an enlarged section on the line 4—4 of Fig. 1;

30 Figs. 5 and 6 are perspective views of details of the tension device;

Fig. 7 is a top view of the tension device when in operation;

Fig. 8 is a section on the line 8—8 of 35 Fig. 7; and

Fig. 9 is a section on the line 9—9 of Fig. 8.

Referring to the drawings in detail, 5 denotes, as a whole, our improved shuttle. Its base member 6, which is principally of wood, is formed with the customary elongated guideway 7 on one side and the rack 8 on the opposite side, with upper and lower plates 9 and 10, respectively. These plates 45 are composed of aluminum or other suitable metal, and are held together by pins 11. The upper base plate 9 is lenticular in outline, its convex sides being intended to co-operate with another similarly shaped plate, herein- 50 after to be described, to protect the weft thread on the bobbin from the warp threads on the loom when in operation. The upper base-plate 9 also provides a support for the side members 12 and 13, which form an arch

or guard for the cop 14 carried by the bobbin 14'. The side members 12 and 13, in this instance, are made of aluminum, and, besides being made of light metal they are cored to further reduce their weight, but they may also be made of wood. 55

The side members 12 and 13 are each transversely divided into two parts, as clearly indicated in Fig. 1, the side member 13 being hinged, as at 13', so that the upper portion of the arch may be opened and turned to one side to facilitate the insertion or removal of the bobbin. This feature together with the vertical stationary bobbin and our special tension device enables us to increase the capacity of the bobbin without 65 increasing the size of the shuttle. The side members are normally held securely together by a pin 15 working in a suitable keeper as at 16 in the side member 12, and having a lateral spring-pressed pin 16' working in 70 a groove in the pin 15.

The bobbin 14' is held in relatively stationary position on a post 17, fixedly mounted in said base-plate 9 and having a spring-pressed pin 18 working laterally in its side 75 to engage a corresponding groove on the interior surface of the bobbin, and the weft-thread 19 is drawn from the cop through a feeding or tension device, to be described, and out of the shuttle through the eye 20. 85

The tension device, designed by us with special reference to its use in connection with the vertical stationary bobbin, consists of a "drag" A and a take-up device B, both located in the forward part of the arch. 90

The "drag" A consists of an immovable member C and a movable member D, separately shown in perspective in Figs. 5 and 6, the immovable member being fixedly mounted on a plate 21 fitted into grooves 22 95 in the sides of the arch and removably held in place by spring-pressed pin 23. The immovable member C consists of a thin strip of metal, having a straight portion 24 extending partially across the interior of the 100 forward portion of the arch and snugly fitting against one of its sides, and an angular portion 25, both parts being perpendicular to the plate 21 to which they are fixedly attached by flange 26 and rivets or other fastening means, as at 27.

The upper portion of the same member is secured against lateral movement by flange

28, into a suitable opening in which, and also in the arch, a pin or screw is inserted, as at 29. The immovable member C has horizontal cut-a-way portions 30, extending substantially across the straight portion 24 and the angular portion 25 leaving bars 31, within which cut-a-way portions or slots 30, oscillate the fingers of the movable member D now to be described. On one of the bars 31 is an outwardly-extending pin 31' which cooperates with the angle of the fingers of the movable member D to keep the thread in a direct path to the eye 20.

The movable member D likewise consists of a thin strip of metal having cut-a-way portions 32, leaving fingers 33 adapted to oscillate, as before stated, between the bars 31 of the immovable member and to exert a gentle "drag" upon the weft-thread carried by the bobbin and passing between the said bars and fingers. In order to adapt the fingers to perform this function properly, they are made, preferably, with backwardly-bent portions or phalanges 34 and outwardly-bent portions or phalanges 35, the latter acting as stops to limit one movement of the fingers.

The movable and immovable members are pivotally connected to each other by means of a pin 36 passing through suitable perforations in a downward extension 37 of the flange 28 on the immovable member C and ears 38 of the movable member D to a seat in the plate 21.

Means are provided for causing the fingers 33 to yieldingly press upon the thread as it passes between them and the bars 31, to prevent the thread from being too freely drawn from the bobbin. This pressure means consists, preferably, first, of the spiral springs 39, one end of which is attached to the arm 40 extending from the body of the movable member D; second, a control rod or bridle 41 having one end pivotally secured to the pin 42 fixedly mounted in the plate 21, said bar having an eye, as at 43, with its loose end bent downwardly to make a set pin 44, which may be inserted in any of the series of perforations 45 in the plate 21. As the spring 39 has its end opposite the arm 40 connected to the control rod or bridle 41, the force exerted by said spring, and, consequently the tension on the thread from the bobbin, through the fingers 33, may be increased or diminished at will by inserting the point of a lead-pencil or the like into the eye 43 of the control rod 41 and with the end of the pencil, placing the set-pin into the hole that will give the desired tension. The control rod or bridle 41 keeps the end of the spring to which it is attached in place and in the path of the perforations intended for the set-pin.

As is well known, between the different movements of the shuttle, a certain amount

of slackness in the thread occurs. We have provided for taking up this by a take-up device shown in Figs. 1, 2, 4, 7 and 8 of the drawings. In a bracket 46 attached to the under side of the plate 21 is an outwardly extending fixed pin 47, to the outer end of which is pivotally connected the arm 48. This arm 48 is elongated and curved, as shown in Fig. 4, its curve conforming to the shape of the abutting plate 49 with which it co-operates and is next to be described. The arm 48 is controlled by a spiral spring 50, which causes it to occupy the position shown in Figs. 1, 2 and 4, and at its loose end has a hook or eye 51 for holding the thread before passing out of the shuttle through the eye 20.

The plate 49 has a two-fold purpose. First, it limits the backward movement of the arms 48 under the influence of the spring 50, thereby preventing the arm from coming in contact with the thread on the bobbin, and, secondly, its convex sides 52, as shown in Fig. 4, co-operates with similar sides of base-plate 9 to provide a guard for the thread on the bobbin when the shuttle is passing through the warp threads of the loom. The plate 49 is also provided with an annular opening 53 to allow full play for the thread as it is drawn from the periphery of the cop held by the stationary bobbin. This annular opening in the plate 49 is clearly shown in Fig. 4. It will now be understood, therefore, how the arm 48 of the take-up device co-operates with the necessary features of the plate 49 in order to perform its own particular function.

The entire tension device carried by the plate 21 may be readily removed by first withdrawing the pin 20 and then the plate 21.

In addition to the features of the plate 21 hereinbefore referred to, it has a small central opening, as at 54, through which the thread passes on its way from the bobbin to the tension device.

The course taken by the thread through the tension device is, preferably, a zigzag one, as clearly shown in Fig. 2 of the drawing, going, first, over the lower bar 31 then around one side of the lower finger 33, then under the middle bar 31 and one side of that bar, and so on, through the remaining fingers and bars. As the thread is thus drawn between the bars 31 and fingers 33, the latter are drawn back against the action of spring 39 and caused to assume the position relatively to the bars shown in Fig. 9. Before going through the outlet eye 20, the thread passes through the hook or eye 51 at the outer end of the arm 48. Whenever slackness of the thread occurs, the arm 48 in taking up this slack, under the influence of spring 50, assumes somewhat the position shown in Fig. 1. When the thread is pulled,

ing from the bobbin the arm 48 under the influence of spring 50 takes the position shown in Fig. 7.

It will, therefore, be understood that the 5 take-up member B has a double function; for, besides acting to take up slack in the weft thread, it co-operates with the member A in exerting a normal tension on the thread as it leaves the shuttle.

10 It is obvious that the tension on the thread in passing through our improved tension device will be uniform at all times, irrespective of the size of the bobbin, or whether it is full or nearly empty, and that, 15 consequently, there is less liability of breaking the thread. It is also obvious that we have largely increased the capacity of the shuttle with no increase in its size, due to our compact tension device and the fact that 20 we can remove the upper part of the arch and mount therein a non-rotative bobbin completely filling the arch from side to side which would not be possible with a rotating bobbin.

25 It will be evident that modifications may be made in the structure and arrangements of the parts of our device without departing from the scope of our invention.

Without limiting ourselves to the exact 30 construction shown and described, what we claim is:

1. A shuttle comprising a base, a hinged arch connected to the base, and a stationary bobbin within the arch and removably connected to the base, the longitudinal axis of the bobbin being perpendicular to the base of the shuttle.

2. A shuttle comprising a wooden base 40 having a metal plate with extending convex sides to protect the weft thread from the shed of the loom, a hinged arch connected to the base, a stationary bobbin within the arch and removably connected to the base, the longitudinal axis of the bobbin being perpendicular to the base of the shuttle.

3. A shuttle comprising a base, a hinged arch connected to the base, a stationary bobbin within the arch and removably connected to the base, the longitudinal axis of the bobbin being perpendicular to the base, and means for applying a tension to the thread after it is drawn from the bobbin.

4. A shuttle comprising a base, an arch connected to the base, a stationary bobbin 55 within the arch and removably connected to the base, and take-up means for the weft thread, one element of which is a plate with extended convex sides to protect said thread from the shed of the loom.

5. A shuttle comprising a base one element of which is a plate with convex sides, an arch connected to the base, a stationary bobbin inside the arch and removably connected to the base, and take-up means for 65 the weft thread, one element being a plate

with extended convex sides co-operating with the plate of the base to protect said thread from the shed.

6. A shuttle comprising a wooden base having a metal plate with extended convex 70 sides to protect the weft thread from the shed of the loom, a hinged arch connected to the base, a post fixedly mounted on the base, and a non-rotatable bobbin removably connected to said post, the longitudinal axis 75 of the bobbin being perpendicular to the base of the shuttle.

7. A shuttle comprising a base, a hinged arch connected to the base, a post mounted on the base, and a non-rotatable bobbin removably connected to said post, and take-up 80 means applied directly to the weft thread after it is drawn from the bobbin.

8. A shuttle comprising a base, a hinged arch connected to the base, a post mounted 85 on the base, and a non-rotatable bobbin removably connected to said post, and take-up means applied directly to the weft thread 90 after it is drawn from the bobbin, one element of which is a plate with an annular opening for play of the thread and having extended convex sides to protect said thread from the shed of the loom.

9. In a shuttle, a tension device comprising a plate, an immovable member having 95 one or more bars mounted on said plate, and a movable member having one or more fingers adapted to move between said bars, said fingers having a plurality of phalanges, one of said phalanges acting as a stop to 100 limit one movement of the fingers, and means for pressing the fingers into position between the bars.

10. In a shuttle, a tension device comprising a plate, an immovable member mounted 105 thereon having one or more bars, and a movable member connected thereto having one or more fingers adapted to move between said bars, said fingers having a plurality of phalanges, one of said phalanges acting 110 as a stop to limit one movement of the fingers, and guide means extending from one of the bars of the immovable member for holding the weft thread to its course to the shuttle outlet.

11. A tension device comprising a plate, an immovable member mounted on said plate having a plurality of bars spaced apart, and a member having one or more fingers adapted to oscillate between said bars, said finger or fingers having a portion bent into a plane angular to that of the remaining portion and to that of the bars, and spring means for actuating the movable member.

12. A tension device comprising an immovable member having a plurality of bars spaced apart, an outwardly extending pin connected to one of said bars, a movable member having one or more fingers adapted 130

to oscillate between said bars with a portion bent into a plane angular to that of the remaining portion of the finger or fingers, said bent portion or portions co-operating 5 with said pin to prevent lateral movement of the weft thread, and yielding means for actuating the movable member.

13. A tension device comprising a plate 10 perforated for the passage of the weft thread, a stationary member mounted on said plate and having a plurality of bars spaced apart, a pivoted member having a finger adapted to oscillate between said bars, a spiral spring connected to said second member and means for adjustably connecting the spring to said plate.

14. A tension device comprising a plate 15 perforated for the passage of the weft thread, and also having a series of perforations for a set pin, a stationary member mounted on said plate and having a plurality of bars spaced apart, a pivoted member having a finger adapted to oscillate between said bars, a spiral spring connected 20 to said second member and having a set pin for insertion in any of the series of perforations in the plate for adjusting the tension on the weft thread.

15. A tension device comprising a plate 25 perforated for the passage of the weft thread and also having a series of perforations for a set pin, a stationary member mounted on said plate and having a plurality of bars spaced apart, a pivoted member having a finger adapted to oscillate between said bars, a spiral spring connected 30 to said second member and having a set pin for insertion in any of the series of perforations in the plate for adjusting the tension on the weft thread, and a bridle connected 35 to said spring for holding the latter in inoperative position.

16. In a shuttle having an arch, a plate 40 removably connected thereto, a tension device mounted on one side of said plate comprising a movable member and an immovable member, the one having fingers and the other bars, movable one within the other, and yielding means for operating the movable member, together with a take-up device 45 mounted on the opposite side of said plate comprising a pivoted, spring-pressed, elongated arm, having means on its free end for loosely holding the weft thread and adapted to normally deliver the same against 50 the action of its spring directly to the outlet, and to take up slack under the action of its spring by movement away from the direct line of travel of the thread.

17. In a shuttle, the arm mentioned in the 55 foregoing claim together with a plate having a central opening to allow for the play of the weft thread drawn from the periphery of the cop and adapted to limit the movement of said arm under its actuating 60 spring.

18. A shuttle comprising a base-piece on 65 which the bobbin is mounted, an arch connected to the base, a stationary bobbin within the arch and removably connected to the base, the longitudinal axes of the bobbin being perpendicular to the base of the shuttle, and convex guard-plates above and below the bobbin.

19. A shuttle comprising a base-piece on 70 which the bobbin is mounted, an arch mounted on said base-piece and embracing the bobbin, convex guard-plates above and below the bobbin, together with tensioning and take-up devices mounted on the upper 75 guard-plate and within the arch.
